UNITED STATES PATENT OFFICE.

FRANCIS G. BRISTOW, OF SYDNEY, AUSTRALIA, ASSIGNOR TO CHICAGO FLEXIBLE SHAFT COMPANY, A CORPORATION OF ILLINOIS.

HANDHOLD JACKET FOR POWER-OPERATED SHEEP SHEARS AND THE LIKE.

Application filed August 9, 1924. Serial No. 731,232.

To all whom it may concern:

Be it known that I, FRANCIS G. BRISTOW, a subject of the King of Great Britain, and a resident of Sydney, Australia, have invented certain new and useful Improvements in Handhold Jackets for Power-Operated Sheep Shears and the like, of which the following is a specification, reference being had to the accompanying drawings, forming 10 a part thereof.

The purpose of this invention is to provide an improved jacket or sheath for the hand-hold of a power-operated sheep shearing tool which shall obviate the difficulties experienced with and defects in the use of the handle coverings which have heretofore been employed. It consists in the elements and features of construction shown and described, as indicated in the claims.

20 In the drawings:

Figure 1 is a perspective view of a known form of power-operated sheep shears equipped with the hand-hold jacket or sheath which characterizes the present invention.

Figure 2 is an inverted plan view of the same.

Figure 3 is a plan view of the sheath unlaced and removed from the tool.

30 Figure 4 is a section at the line, 4—4, on Figure 1.

Figure 5 is a section at the line, 5—5, on Figure 2.

It has long been customary to provide for the hand-hold or hand-gripped portion of a power-operated sheep shears a jacket or covering which shall afford a more comfortable and secure grasp for the hand of the operator than that which is afforded by the smooth and usually polished metal surface of the body or casing of the tool. These heretofore employed jackets or covers have been made of a single layer of canvas or leather and have not been found satisfactory.

45 The leather absorbs the lubricating oil which is liable to escape more or less from the interior of the tool and soon becomes stretched out of shape so that it is liable to slip on the tool body, and also becoming 50 greasy upon the outer surface, loosens the grip of the operator, and through these tendencies to slip in the operator's hand and on the tool body, greatly increases the muscular effort necessary to obtain proper grasp 55 for operating the tool, and thereby reduces

the rate at which the operator can manipulate the tool in shearing. When the jacket is made of canvas or like textile fabric, this fabric becomes clogged and slippery both in the hand of the operator and on the body of the tool, even more rapidly and embarrassingly than in the case of leather. Felt and woolen textile fabric offer some advantage over leather and canvas because the woolen felt and textile fabric have some capacity 60 for absorbing the oil and perspiration and preventing the surface from becoming greasy and slippery after so short a use as in the case of leather and canvas, but felt and woolen textile fabric both lack the tenacity 65 or resistance to stretching which is necessary to keep the jacket fitted snugly on the body of the tool, as it must be to perform the function for which it is provided, and when the jacket is made of such material, in order 70 to be at all effective, it must be positively secured to the body of the tool at many points, no reliance being placed upon the frictional hold for which it must be—and continue—tightly stretched about the metal 75 body of the tool; and when such multiplicity 80 of securements is provided, the jacket is necessarily destroyed every time it is removed for opening the tool for any attention which 85 may be required to the interior mechanism.

In the present invention the defects and disadvantages of all these forms of jacket which have heretofore been employed, are substantially obviated by making a jacket or sheath for the hand-hold, consisting of an 90 inner or lining layer or ply of leather, and an outer or cover layer of woolen felt, the two layers being secured together over their entire contacting surfaces by an interposed 95 layer of material which may be termed glue or cement, being strongly adhesive, and water and oil proof, so that neither the oil from the tool which may reach the leather, nor the perspiration from the hand which reaches the felt, can penetrate this intervening layer. The jacket formed of these three layers is constructed flat, as seen in Figure 3, of such contour and dimensions that when folded about the hand-hold portion of the tool the opposite edges may meet and be laced together in a substantially straight line in a plane axial with respect to the hand-hold, notwithstanding the variation in diameter of the hand-hold at different parts of the length thereof, the varia- 100

tion in circumference of the hand-hold at the different parts being provided for by corresponding variation in the width of the flat-form sheath, as seen in Figure 3. The drawings show the tool body of the customary form, comprising the head, A, and hand-hold portion, A¹, the latter having an enlargement at A², which accommodates the driving connection from the power shaft, B, 10 to the cutter operating lever, C. The enlargement or swell at A², as is well understood, in addition to the function of accommodating the operating connection as mentioned, has the further function of affording comfortable and secure grasp to the hand of the operator, tending to prevent the hand from slipping longitudinally; and in grasping the tool at this swell for this advantage, the thumb and first finger of the 20 operator will advantageously for guiding the tool be pressed upon the opposite diverging sides of the head, A; and the jacket is therefore formed so as to have lugs or extensions covering these diverging sides of the head. 25 In detail, the jacket or sheath, indicated at large by the reference letter, D, comprises as above described, an inner or lining layer of leather, 10, and an outer cover layer of woolen felt, 11, in an intervening oil-and- 30 water-proof adhesive layer, 12, which secures the felt and leather layers permanently together. This adhesive layer is desirably made of a strong quality of glue which is flexible when fully dry and set, so that it 35 does not prevent the folding of the sheath about the hand-hold nor crack in such folding. The dimensions of the jacket, D, may be understood from Figure 3 as varying in width at different parts of its length, corresponding to the variations in circumference of the hand-hold of the tool at corresponding points in the length of the latter, which causes the jacket in plan view to be 40 tapered widening from the rear end for about three-fifths of its entire length, and then tapered narrowing toward the forward end. The forward end is recessed as seen at D¹, forming two forwardly projecting lugs, D², D³, which by reason of the notch or recess 45 between them are adapted to be spread apart when the jacket is folded upon the tool so as to fit upon and cover the opposite sides of the head, A, where the same is grasped by the thumb and first finger of the operator 50

as mentioned. The opposite longitudinal edges of the sheath are eyeleted as indicated by the eyelets, D⁴, and lacing, E, is provided for drawing the two edges together to stretch the jacket tightly about the hand-hold. 55

In practice it has been found that by 60 reason of the frictional hold of the leather on the metal of the tool body when the jacket is tightly laced thereabout as described, and the adaptation of the felt to afford a secure and comfortable hold for the grasp of the 65 operator, and the imperviousness of the adhesive layer, 12, to both the perspiration and the oil, a jacket of this construction substantially obviates all the defects and disadvantages above mentioned as pertaining to the 70 single layer of leather, canvas or woolen felt or textile fabrics heretofore employed for like purpose. 75

To insure against the jacket at any time starting to slip from the position at which it is originally located on the casing of the tool, there is desirably provided a means of positive engagement of the jacket at one point with the casing, as by a screw, F, for 80 which a hole is bored and tapped in the casing and a hole positioned for registering therewith is made in the jacket as seen at d. 85

I claim:—

1. A hand-hold sheath for a sheep shears and the like, consisting of a jacket made of flat material flexible for being folded closely about a handle portion of the tool and provided with means for lacing its edges together for securing it on the tool handle, the same consisting of an inner layer of leather for contact with the tool handle, an outer covering layer of wool felt for contact with the hand of the operator, and means for securing the two layers together over substantially their entire area. 90 95

2. In the construction defined in claim 1, the means for securing the two layers together being a third layer intervening between the leather and the wool felt consisting of adhesive water-and-oil-proof material for protecting the leather layer from moisture and oil entering through the wool felt layer. 100

In testimony whereof, I have hereunto set my hand at Chicago, Illinois, this 5th day of August, 1924. 105

FRANCISS G. BRISTOW.
